UNITED STATES PATENT OFFICE.

WARREN G. SLATER, OF FREMONT, MICHIGAN.

DESIGN FOR A BUTTON-FASTENER.

SPECIFICATION forming part of Design No. 18,281, dated April 24, 1888.

Application filed February 16, 1888. Serial No. 264,261. Term of patent 7 years.

To all whom it may concern:

Be it known that I, WARREN G. SLATER, a citizen of the United States, residing at Fremont, in the county of Newaygo and State of Michigan, have invented and produced a new and original Design for Button-Fasteners; and I do declare the following to be a full, clear, and exact description of the same, reference being had to the accompanying drawings, forming a part thereof.

Figure 1 is a front view of my newly-designed fastener; Fig. 2, an edge view projected from Fig. 1. Figs. 3 and 4 are sectional views taken in the planes indicated, respectively, by dotted lines $x^1 x^2$ and $y^1 y^2$.

The leading feature of my design consists in an acute-angular arch, A, composed of transversely rounded parts $a a'$, terminating in a curve, a' , which is the apex of the arch. The lower or terminal extension of this arch presents rounded configurations $a^1 a^2$ externally and obtuse angles $x^1 x^2$ internally, and from the said configurations and the obtuse angles extend limbs B B, which are tapered externally to the points $c c'$ from the points $a^1 a^2$, as shown in Fig. 1, leaving the internal edges, $e e'$, parallel.

By reference to Fig. 2 it will be observed that the configuration of the design presents two parallel edges extending between a semicircle, a' , and a semicircle, c ; also, that the face of the limb in edge view presents ridges b and valleys b' .

The leading feature of my design consists in an angular arch having rounded configura-

tions at its exterior terminal points and tapered limbs when viewed in elevation, having rounded ends c and external ribs, which latter have valleys b' , as shown in Fig. 2 of the annexed drawings.

In cross section the arch A, taken at any point above the angles $x^1 x^2$ and the curves $a^1 a^2$, is a semicircle, as shown by Fig. 3. The limbs B, taken at any point between the rounded ends $c c'$ and said points $a^1 a^2 x^1 x^2$, present a rectangle having hills and valleys, as above stated, and shown in the annexed drawings. It will thus be seen that when my design is viewed in elevation, as in Fig. 1, it presents to the eye the combined effect of a thickened angular arch having tapered extensions, and when viewed edgewise it presents rounded ends, parallel sides, and series of elevations and depressions.

I claim—

The design for a button-fastener herein described and shown, the same consisting of the transversely rounded and straight angular arched portion A, terminating in tapered limbs whose external surfaces are parallel to each other, whose ends c are rounded, and whose external beveled sides present raised ribs and valleys.

In testimony whereof I affix my signature in presence of two witnesses.

WARREN G. SLATER.
